UNITED STATES PATENT OFFICE

160,193

BILLFOLD

Jerry Moss, Chicago, Ill.

Application April 12, 1950, Serial No. 9,153

Term of patent 3½ years

(Cl. D87—3)

To all whom it may concern:

Be it known that I, Jerry Moss, a citizen of the United States, and a resident of Chicago, in the county of Cook and State of Illinois, have invented a new, original, and ornamental Design for a Billfold, of which the following is a specification, reference being had to the accompanying drawings, forming a part thereof, and in which:

Fig. 1 is a perspective view of a billfold, showing my new design;

Fig. 2 is a perspective view of the inside thereof;

Fig. 3 is a plan view of the outside of the billfold in opened condition;

Fig. 4 is an enlarged fragmentary view illustrating the edge trimming.

I claim:

The ornamental design for a billfold, as shown and described.

JERRY MOSS.
